INK FOUNTAIN STRUCTURE

Henri E. Peyrebrune, River Forest, and Harry T. James, Chicago, Ill., assignors, by mesne assignments, to Michle Printing Press & Manufacturing Company, Chicago, Ill., a corporation of Delaware

Application March 11, 1947, Serial No. 733,962

7 Claims. (Cl. 101—364)

1

The invention relates to inking mechanism for printing presses and has reference in particular to improved structural features applicable to ink fountains having a collapsible bottom wall such as basically disclosed in the Clark Patent No. 1,231,567, granted July 3, 1917.

The fountain structure of the above identified patent embodies a collapsible bottom wall having a fountain blade of flexible metal secured thereto and located with an edge in close proximity to the ink fountain roller when the bottom wall is in closed position. The bottom wall may be collapsed by moving the same in a direction away from the roller whereby to render the parts accessible for cleaning purposes. Also the structure of the patent embodies adjustable means for adjusting the fountain blade locally along its width for obtaining the desired distribution of ink.

The present invention aims to improve the ink fountain structure of the above patent by providing toggle means connecting with the collapsible bottom wall of the ink fountain in combination with a worm gear drive for actuating the toggle means whereby the collapsible bottom wall may be moved to and from collapsed and operative positions and securely locked in closed operative position by said toggle means which have location beyond a dead center position for such purpose.

In the operation of printing presses which are run at comparatively high speeds, one is confronted with the problem of maintaining the predetermined ink supply constant during the entire run of a printing job, particularly so where multicolor work is involved. For accomplishing this, it is essential to provide means whereby the ink fountain setting, that is to say, the metering of the volume of ink supplied to the ink distributing roller system by the ink fountain, must be maintained constant throughout the entire printing job.

In certain types of ink fountain structures, including the collapsible fountain disclosed in the above identified patent to Clark, the ink fountain blade is maintained in its cooperative relation with the fountain roller mainly by the force of gravity on the fountain bottom wall and associated parts. No provision is made whereby any disturbance of the fountain setting brought about by vibration or other causes, can be avoided.

It is therefore one of the primary objects of our invention to provide effective means whereby the fountain blade and its support shall be se-

2

curely held in predetermined setting relation with the fountain roller, to thereby maintain the ink supply from the fountain at a predetermined rate.

Another object of the invention is to provide improved means for operating the collapsible bottom wall of an ink fountain comprising toggle mechanism wherein one pair of links of said mechanism is connected by an eccentric to provide for adjustment of the toggle links at one end of the fountain with respect to the toggle links at the opposite end.

In the fountain structure of the invention the eccentric arrangement is incorporated in the toggle links at that end of the fountain which is farthest from the worm gear drive where the operating crank is located and as a result the eccentric arrangement provides a "preloading feature" which assures that this far end of the collapsible bottom wall of the fountain is locked in operative position simultaneously or preferably before the other end, i. e. that end adjacent the operating gears.

Still another object resides in the provision of an operating shaft for the toggle means in the form of a sleeve supported for rotation on a solid shaft or rod fixedly mounted at its respective ends in the frame of the press, whereby maximum strength and rigidity is obtained in the operating mechanism for the collapsible bottom wall.

A further object is to provide ink fountain structure having a collapsible bottom wall with toggle means and a worm gear driving for actuating the same, and wherein the bottom wall is capable of unit adjustment to vary the position of the ink fountain blade with respect to the fountain roller whereby to regulate the quantity of fed ink across the entire width of the plate without disturbing the setting of the local adjusting screws.

With these and various other objects in view, the invention may consist of certain novel features of construction and operation as will be more fully described and particularly pointed out in the specification, drawings and claims appended hereto.

In the drawings, which illustrate an embodiment of the invention, and wherein like reference characters are used to designate like parts;

Figure 1 is a rear elevational view showing ink fountain structure equipped with the improved features of the invention;

Figure 2 is a transverse sectional view show-

ing the toggle means in position to hold the collapsible bottom wall closed with the edge of the fountain blade operatively located in close proximity to the fountain roller; and

Figure 3 is a side view, partly in elevation and partly in section, showing the movable bottom wall in collapsed position to facilitate cleaning of the fountain roller.

Referring to the drawings, the embodiment selected for illustrating the present invention essentially consists of a frame providing the end walls 10 and 12 of the ink fountain which additionally includes a bottom wall 14 and an ink fountain roller of metal designated by numeral 15. The ink fountain roller is formed with trunnions 16 which extend through the end walls 10 and 12 and into bearings 17 and 18 provided on said walls respectively to rotatably support the roller 15. At the right hand end of the fountain, as shown in Figure 1, it will be observed that the trunnion 16 extends beyond its bearing 18, the extending end being reduced in diameter for supporting the ratchet wheel 20 which is securely fixed thereto for the purpose of transmitting rotation to the fountain roller 15. This reduced end also carries the actuating lever 21, the latter being loose on the shaft and thus capable of rotation independently of the shaft. The actuating lever 21 is preferably held on the end of this trunnion by a retaining bolt 22. The handle end 23 of the actuating lever 21 carries the pawl 24 which engages the teeth on ratchet wheel 20. A pivoted latch 26 is mounted on the outer wall of the fountain frame 25. This latch is urged in an upward direction by the coil spring 27. The coil spring yieldingly holds the latch in contact with the teeth of ratchet 20 and is constructed and arranged to prevent rotation of the ratchet and thus rotation of the ink fountain roller in a clockwise direction, Figure 3. The depending end 28 of the actuating lever 21 pivotally connects with rod 30 as at 31, the said rod being actuated in any conventional manner by an operating part of the press to thereby cause oscillating movement of the actuating lever 21. As a result of this movement of the lever and the structure including the ratchet, intermittent rotation is imparted to the ink fountain roller.

The bottom wall 14 is integral with the two depending sections 32 one of which being provided at each end of the fountain and which sections are pivotally supported by a shaft 33 mounted in the fountain frame 25. The bottom wall 14 and said depending section 32 therefore have movement as a unit about the shaft 33 as an axis. The fountain blade 34 is fixed to the upper surface of the wall 14 and a cavity or recess 35 is formed in said wall so that the inner end of the blade adjacent the roller 15 will be free and thereby capable of flexing movement in a direction toward and from the roller when the fountain is in closed operative position. A series of closely spaced and conventional set screws 36 are arranged along the bottom wall. Said screws contact at their inner ends with the flexible end of the fountain blade and may be adjusted for regulating the ink supply along the entire width of the fountain roller 15 so as to obtain the desired supply of ink for the form, as is well known in the art of printing.

The shaft 37, which is suitably supported and secured against rotation in horizontal position adjacent the ink fountain structure by the frame of the press or by any other stationary part thereof, rotatably supports the sleeve 38, which

latter extends substantially across the entire width of the ink fountain. At its right hand end, as shown in Figure 1, the sleeve 38 has suitably fixed thereto the worm gear 40, and at this end shaft 37 extends through and beyond portion 25 of the frame, which portion journals the worm 41 having meshing relation with worm gear 40 and constituting the driving means for said gear. Worm 41 is suitably fixed to an operating shaft 42 journalled in bearings 43 integral with the fountain frame portion 25. Said shaft 42 projects beyond its left hand bearing, as shown in Figure 2, for receiving the crank 44. Said crank, having the handle 46, is releasably engaged with the projecting portion of shaft 42, and by means of pin 45 rotation of the crank is imparted to the worm gear 41 and thus to gear 40 to cause rotation of sleeve 38.

Sleeve 38 forms part of the toggle mechanism for actuating the collapsible bottom wall 14 of the ink fountain. The spaced links 48 and 50 are formed integral with the sleeve 38, the link 48 being located at the end of the sleeve farthest removed from gear 40, and the link 50 being located relatively adjacent the gear end of the sleeve. Link 48 is connected to link 51, having pivotal connection at its upper end as at 52 to the collapsible wall 14 of the fountain. In a similar manner link 50 pivotally connects with link 53 which is pivoted at its other end to the bottom wall 14 of the fountain as at 54. It will therefore be observed that by rotating the sleeve 38 by means of the crank 46, the toggle means, comprising links 48, 51 and links 50, 53, will be simultaneously actuated to move the bottom wall 14 of the fountain to and from its operative and collapsed positions.

In accordance with the invention the links 48, 51 are pivotally connected by means of an eccentric 55. This eccentric is integral with its stud shaft 56, mounted in link 48, as shown in Figure 1, the stud shaft and thus the eccentric, by means of its shoulder bearing against the link 48, being fixedly held in adjusted position by bolt 57 having the securing nut 58. Link 51 is free to pivot about the eccentric 55. The other toggle means which comprises links 50, 53 are joined in the usual manner by a pivot pin or bolt designated by numeral 60 and which pin is suitably held in position by a nut 61 threaded onto it. The effect of the eccentric 55 connecting links 48, 51, is to provide for adjustment of the pivot center of said connection and which pivot center may therefore be shifted laterally beyond the center line of the links to the extent permitted by the eccentric. No such adjustment is provided for links 50, 53. The eccentric arrangement is located at the far end of the ink fountain, or, in other words, at the end farthest removed from the gear drive including the worm gears 40 and 41, and thus at the end away from the operator. With the bottom wall 14 in closed operative position as shown in Figure 2, it will be seen that the toggle links are beyond dead center position to a slight extent sufficient to securely lock the toggle mechanism and the bottom wall rigidly in their closed position and against adjustable stops 62 for the purpose of eliminating any play in the assembly due to manufacturing tolerances and to prevent inadvertent opening which otherwise might occur as a result of vibrations of the press or the like. The position of the toggle links past dead center can also be varied by said adjustable stops 62 which are preferably threaded into frame 25 and

extend outwardly from the frame for contact with the links 51 and 53, respectively. In collapsed position of the bottom wall the stops 63 are in contact with the arcuate portions of links 48 and 50, respectively.

For ink fountains of considerable width the eccentric feature has proven desirable and effective for the purpose of assuring that the far end of the movable bottom wall and therewith the fountain blade will be locked in closed position before the end near the operator is locked. Adjustment of the eccentric can also be resorted to for eliminating any irregularities in the construction of the bottom wall or the ink plate. For example, if one end of the fountain blade should be a trifle wider or narrower than the other end, which might be the result of inaccuracy in the grinding operation, an appropriate adjustment of the eccentric could be made to overcome this.

The toggle mechanism in combination with the worm gear drive also enables a collective positioning of the blade toward or away from the fountain roller to provide a unit adjustment of the same for regulating the amount of ink fed across the width of the fountain and which does not interfere with the individual setting of the adjusting screws.

What is claimed is:

1. In an ink fountain, the combination with side walls journaling a fountain roller, of a pivoted bottom wall having a closed and an open position with respect to said fountain roller, toggle mechanism for actuating said bottom wall including a pair of toggle links at each end of the bottom wall, and eccentric means pivotally connecting the links of one pair, whereby to provide for adjustment of the pivot center of the links of said pair to insure proper positioning of the bottom wall with respect to the fountain roller in its closed position.

2. In an ink fountain, the combination with a frame providing the side walls of an ink trough, a fountain roller journaled by said side walls, a bottom wall for said ink trough, a fountain blade fixed to said bottom wall, means mounting the bottom wall for movement independently of the side walls to a closed or operative position in which position the edge of the fountain blade is in close proximity to the roller and an open or inoperative position in which the blade is moved away from the roller and the bottom wall is completely clear of said side walls to facilitate cleaning of the fountain, toggle mechanism for actuating said bottom wall including a pair of toggle links at each end of the bottom wall, a sleeve supported for rotation on a stationary shaft one link of each pair having pivotal securing to the bottom wall, the other link of each pair being fixed to and actuated by said sleeve, means pivotally joining the links of each pair including an eccentric for one pair of said links, whereby said eccentrically connected links are capable of adjustment by rotation of said eccentric for preloading the bottom wall to assure the positioning of both pairs of links beyond dead center position, and adjustable stops associated with said links for predetermining the extent of their movement beyond dead center and cooperating with said links to lock the toggle mechanism and thereby the bottom wall rigidly in their closed or operative position.

3. In an ink fountain structure for printing presses the combination of a fountain roller, a movable bottom wall having an open and a closed

position with respect to the fountain roller, toggle mechanism for actuating said bottom wall including a pair of toggle links at each end of said bottom wall, adjustable stops provided on the ink fountain for contact with one link of each pair, said links having a position beyond dead center and contacting said stops to thereby lock the bottom wall in closed position, said stops also providing means for predetermining the extent beyond dead center said links may be positioned, eccentric means pivotally joining the links of one pair whereby preloading of the bottom wall is provided for to assure the locking of both pairs of links beyond said dead center position when closing said bottom wall, and a worm gear drive for actuating said toggle mechanism.

4. In an ink fountain structure for printing presses, the combination of a fountain roller, a movable bottom wall having an open and a closed position with respect to the fountain roller, toggle mechanism for actuating said bottom wall including a pair of toggle links at each end of said bottom wall, adjustable stops provided on the ink fountain for contact with one link of each pair, said links having a position beyond dead center and contacting said stops to thereby lock the bottom wall in closed position, said stops also providing means for predetermining the extent beyond dead center said links may be positioned, eccentric means pivotally joining the links of one pair whereby preloading of the bottom wall is provided for to assure locking of both pairs of links beyond said dead center position when closing the bottom wall, a sleeve mounted for rotation in parallel relation with the bottom wall, one link of each pair being fixed to and actuated by said sleeve, the other link of each pair having pivotal securing to the bottom wall, and a worm gear drive for rotating said sleeve whereby to actuate the toggle mechanism.

5. In an ink fountain structure for printing presses the combination of, side walls, a fountain roller journaled therein, a pivoted bottom wall having a closed and an open position with respect to said fountain roller, adjustable stops carried by said ink fountain, and toggle mechanism for actuating said bottom wall including a pair of toggle links at each end of the bottom wall, the links of one pair being pivotally joined by eccentric means to provide for adjustment of the pivot center of said pair whereby contact of both pairs of links with said stops in a position beyond dead center of said links is assured and all excessive play is taken up, thereby rigidly securing said bottom wall in its closed position.

6. In an ink fountain structure for printing presses, the combination of a frame including side walls, a fountain roller journaled in said walls, a collapsible bottom wall including a fountain blade, mechanism for moving said bottom wall to and from operative and inoperative positions, said bottom wall in inoperative position being collapsed with respect to said fountain roller and clear of said side walls, and an eccentric stud arranged at one end of said mechanism to provide adjustment whereby movement of said fountain blade to a predetermined position with relation to said roller is assured.

7. An ink fountain structure for printing presses, having in combination, side walls, a fountain roller journaled therein, a bottom wall movable toward and away from said roller, a fountain blade carried by said bottom wall, operating means provided adjacent said side walls for moving said bottom wall, means associated

with said operating means for accomplishing adjustment of said blade relative to said roller, and mechanism for actuating said operating means including gears and a member rigidly connecting said operating means, said latter means including an adjustable eccentric stud at the far end of said member whereby torque in said member may be compensated for.
